UNITED STATES PATENT OFFICE.

CHARLES E. WILLEY, OF LOUISVILLE, KENTUCKY.

DRILLING MACHINERY.

SPECIFICATION forming part of Letters Patent No. 701,115, dated May 27, 1902.

Application filed July 6, 1900. Serial No. 22,676. (No model.)

To all whom it may concern:

Be it known that I, CHARLES E. WILLEY, a citizen of the United States, residing at Louisville, in the county of Jefferson and State of Kentucky, have invented certain new and useful Improvements in Drilling Machinery; and I do hereby declare the following to be a full, clear, and exact description of the invention, such as will enable others skilled in the art to which it appertains to make and use the same.

My invention relates to improvements in drilling-machines, and more particularly to improvements in radial and semiradial drills.

15 My invention consists in mounting an electric or other motor on the radial arm, head, or carriage of the drill, and preferably between the supporting-column and the drill-spindle, and in driving therefrom gearing by which the spindle is rotated and the feed mechanism is operated.

25 My invention consists, further, in providing elevating mechanism by which the head may be raised or lowered, said elevating mechanism being also driven from the motor in the head, in forming the pole-pieces of the motor as integral parts of the head, and in the many novel details of combination, construction, and arrangement of the parts.

30 The objects of my invention are to simplify the structure of drilling machinery, and particularly of radial and semiradial drill-presses, to dispense with the devices ordinarily employed for transmitting motion 35 from a counter-shaft occupying a fixed position to the movable head or carriage of the machine, to avoid the use of belts, splined transmitting-shafts, and the like by which power is ordinarily communicated to the 40 mechanism of the movable head of a drill, and to make the mechanism of the drill simple, compact, and self-contained, to make it easy to start and stop the drill, to vary its speed, to raise or lower its head, or to shift

45 its head to one side or the other at will. As radial and semiradial drills are ordinarily constructed power is communicated from a counter-shaft occupying a fixed position with respect to the machine and often or usually 50 placed at the base of the machine to the spindle-driving and automatic feed mechanism through the medium of bolts or splined

shafts and the like. To permit the raising and lowering of the head, to permit it to be swung from one side to the other, and, in 55 case of a radial drill, to permit the head to be moved in and out along the radial arm involves the use of transmitting mechanism of considerable complication for the transmitting of motion from the counter-shaft above 60 mentioned to the drill-spindle and its feeding devices. All of this complication may be overcome by mounting a prime motor directly in or on the drill-carrying head of the machine, and a motor may be so mounted and 65 conveniently masked and placed out of the way and protected from injury by locating the motor in the drill-carrying head of the machine. By so doing all of the complication incident to the transmission of power from a 70 fixed counter-shaft to a vertically, laterally, and often radially movable drill head or carriage is entirely avoided. This is what I do in the machine herein illustrated and described.

75 In the machine herein illustrated and described, the motor is shown not only as carried by the head, but as inclosed within same. This is advantageous as protecting the motor from injury, as providing a structure of the greatest simplicity and least weight. Further, the motor is arranged with its drive or armature shaft in a horizontal plane and located between the drill-spindle and the support. This is an important feature of the invention. The weight of the motor is disposed nearest the point of support, and hence the least strain is exerted on the head. The working or movable parts of the motor, together with the heaviest portion of 80 the gearing, revolve upon horizontal bearings instead of vertically-arranged bearings, such as would be necessary if the motor were arranged vertically. The advantage of one construction over the other is too well known to 85 require detailed description herein.

90 In the drawings, Figure 1 is a right-hand side elevation of a semiradial drill constructed in accordance with my invention. Fig. 2 is a top view of the radial arm, head, or carriage of the drill-press. Fig. 3 is a left-hand side elevation of said radial arm, head, or carriage. Fig. 4 is a vertical section of the 95 head through the axis of the spindle. Fig.

5 is a transverse section of the head through the axis of the armature-shaft to the motor. Fig. 6 is a horizontal section of the "back-gear" mechanism; and Fig. 7 is an irregular horizontal section of the automatic feed mechanism, taken through the axes of the worm and feed shafts.

In the drawings like reference-numerals indicate the same or corresponding parts.

1 designates the base-plate of the machine; 2, the column; 3, the table for supporting the work; 4, the arm carrying the table, and 5 the vertically and laterally movable arm, head, or carriage. This head is mounted upon and may be clamped firmly in position upon the column 2 in the ordinary manner.

6 is the drill-spindle, revolvably mounted in the head in the ordinary manner.

7 is a swivel-head upon the top of the column 2, carrying a pulley 8, over which passes a chain or other flexible connecting member 9, connected at one end to the carriage 5 and at the other end to a counterbalance-weight 10, movable up and down in the hollow column 2 of the machine.

11 is an armature-shaft of an electric motor, mounted in the head 5, said armature having bearings carried by the head 5, as shown in Fig. 5.

12 is the armature.

13-13 are pole-pieces of the armature, formed integrally with the head 5, and 14-14 are the spools or field-windings of the motor.

The motor may be of any usual or suitable construction. I have shown a four-pole motor; but the number of poles of the motor is not material.

In the sides of the head 5 in the vicinity of the motor are apertures 15, which permit the circulation of air around the armature, so as to prevent overheating of the motor.

Upon the armature-shaft 11 is a pinion 16, intermeshing with a gear 17 upon a bushing 18, surrounding a shaft 19. Upon the bushing 18 is also mounted a pinion 20, intermeshing with a gear 21, which gear is connected by a bushing 22 to a pinion 23, intermeshing with a gear 24, mounted upon and keyed to the shaft 19. The bushing 22 is mounted upon an eccentric shoulder of a spindle 25, which spindle is provided with a handle 26, by which it may be rotated, so as to throw gears 21 and 23 out of mesh with gears 20 and 24. Gears 20 21 23 24 form the familiar back gear commonly used in lathes and other machine-tools.

Upon the shaft 19 is a bevel-pinion 27, intermeshing with a bevel-gear 28, mounted upon a vertical shaft 29, having bearings in the head 5. The end of the shaft 29 projects above the top of the head and carries a pinion 30, intermeshing with a gear 31, surrounding the drill-spindle 6 and connected thereto by a spline in the ordinary manner. The pinion 30 also intermeshes with a gear 32, connected to a cone-pulley 33. A vertical shaft 34, having bearings in the head, carries

a complementary cone-pulley 35. These cone-pulleys may be connected by a belt in the ordinary way and permit the rate of feed of the spindle to be varied as desired. The vertical shaft 34 carries a pinion 36, Fig. 1, intermeshing with a gear 37, connected to a bevel-pinion 38, intermeshing with a bevel-gear 39, loosely mounted upon a worm-shaft 40. A hand-wheel 41 is splined to shaft 40 and is provided with a cone 42, lying within a conical recess in the bevel-gear 39 and forming a cone-clutch, by which gear 39 may be placed in driving connection with shaft 40 or may be caused to revolve loosely upon said shaft at will. A nut 42' is provided for the purpose of forcing the cone 42 against the gear 39.

The construction here described is substantially that commonly employed for throwing in and out the automatic feed of a machine-tool.

The worm-shaft 40 carries a worm 43, intermeshing with a worm-wheel 44, mounted loosely upon a feed-shaft 45. Upon said shaft 45 and connected thereto by a spline is a wheel 46, having projecting handles 47, by which it may be rotated. The wheel 46 is provided with a conical recess adapted to connect with a cone on worm-wheel 44, so as to form a cone friction-clutch, and a clamping-nut 48, provided with projecting handles 49, serves to clamp wheels 46 and 44 together or to release the clutch at will. Shaft 45 carries a pinion 50, intermeshing with a feed-rack 51 upon a sleeve 52, which sleeve supports the drill-spindle 6 by means of collars 53 upon the spindle. This also is a common construction. To the bushing 52 is connected a cord 54, which passes over guide-pulleys 55, Fig. 4, and 56, Figs. 1 and 2, and over guide-pulleys 57 and 58, carried by the swivel-head 7 of the machine, and is connected to a counterbalance-weight 59, by which the weight of the drill-spindle is counterbalanced.

The mechanism above described comprises the mechanism for rotating the drill-spindle, for automatically feeding the same both by power and by hand, and for quickly raising and lowering the same. I have also provided a mechanism for automatically raising or lowering the head 5. Upon the lower end of the shaft 60, carrying the cone-pulley 33 and gear 32, there is a gear 61, intermeshing with a gear 62. (Shown in dotted lines in Fig. 2.) Gear 62 intermeshes with another gear 63, which latter gear intermeshes with a gear 64, which forms a part of a screw-nut surrounding an elevating-screw 65, mounted alongside of the column 2. Gears 62 and 63 are carried by a bracket 66, pivoted concentrically on a screw 65, which bracket is provided with a handle 67, by which it may be moved. By moving said handle inward gear 62 may be thrown out of mesh with gear 61, and by moving said handle still farther gear 63 may be brought into mesh with gear 61, gear 62 being then an idler. When gear 62 is in mesh with gear 61, if the motor be operated the head 5 will be

moved in one direction, and if gear 63 be in mesh, the motor being operated, the head will be moved in the other direction.

Upon one side of the head is a starting-
5 rheostat 68, and upon the other side of the head in the vicinity of the column 2 is a speed-regulating rheostat 69.

In the operation of this drill when the armature-shaft revolves power is communicated
10 through the back gears 21 and 23 to the shaft 19 or directly to said shaft if gears 21 and 23 be out of operation, and from shaft 19 power is communicated through bevel-gears 27 and 28 to shaft 29 and pinion 30. From pinion 30 motion is transmitted to gear 31 and thence to the drill-spindle 6. The revolution of the drill-spindle is independent of longitudinal motion thereof, because of the spline connection between gear 31 and spindle 6. From
15 pinion 30 motion is also transmitted to gear 32 and thence through the cone-pulleys 33 and 35 to shaft 34; gears 36 and 37, bevel-pinion 38, and bevel-gear 39. If the cone 42 of the feed-wheel 41 be in contact with the conical recess of gear 39, then the drill-spindle is fed downward slowly and automatically by the pinion 50 and rack 51, pinion 50 being driven from hand-wheel 41, worm-shaft 40, worm 43, worm-wheel 44, friction-cone 46, and shaft 45. The automatic feed may be stopped at any
25 time by turning the nut 42 or the nut 48. The drill may be fed in either direction by hand when the automatic feed is not in operation by means of hand-wheel 41.

30 For quick adjustment of the position of the drill or for quickly raising the same the clamping-nut 48 may be relieved and the required adjustment obtained by turning the handles 47. When the clamping-nut 48 is in contact
35 with the wheel 44, the drill is held stationary, except as it may be moved in either direction by the automatic feed or by turning the wheel 41 by hand, owing to the self-locking action of the worm 43 and the worm-wheel 44.

40 To raise or lower the head 5, the clamping-nuts by which said head is clamped to the column 2 are first relaxed, and then the handle 67 is moved in the proper direction, so as to bring gear 62 or gear 63, as the case may
45 be, into mesh with gear 61.

Having thus completely described my invention, what I claim, and desire to secure by Letters Patent, is—

45 1. In a drill, the combination with a support, a head movably secured thereto, and a revoluble spindle carried by said head, of a motor mounted within said head, and carried

thereby, the drive-shaft of said motor being arranged horizontally and located between said support and said revoluble spindle, a 60 pinion carried by said drive-shaft, back gearing driven by said pinion, a bevel-gear connected to said back gearing, a vertical shaft, a bevel-gear on said vertical shaft and driven by first-mentioned bevel-gear, a pinion on 65 said vertical shaft, and a gear-wheel having a splined connection with the said revoluble spindle, and in engagement with said pinion.

2. In a drill, the combination with a support, a head movably secured thereto, and a 70 revoluble spindle carried by said head, of a motor mounted within said head, and carried thereby, the drive-shaft of said motor being arranged horizontally and located between said support and said revoluble spindle, a pinion carried by said drive-shaft, back gearing 75 driven by said pinion, a bevel-gear connected to said back gearing, a vertical shaft, a bevel-gear on said vertical shaft and driven by first-mentioned bevel-gear, a pinion on said vertical shaft, a gear-wheel having a splined connection with the said revoluble spindle, and in engagement with said pinion, and means for imparting a longitudinal movement to said spindle, driven from said vertical shaft. 80

3. In a drill, the combination, with a support, a head movably secured thereto, and a revoluble spindle carried by said head, of a motor carried by said head and having a horizontal driving-shaft, a gear having a splined 90 connection with the spindle, and gearing for transmitting motion from the motor to said spindle-gear, and including bevel-gears and a vertical shaft driven thereby and carrying a gear intermeshing with said spindle-gear. 95

4. In a drill, the combination, with a support, a head movably secured thereto, and a revoluble spindle carried by said head, of a motor carried by said head and having a horizontal driving-shaft, a gear having a splined 100 connection with the spindle, gearing for transmitting motion from the motor to said spindle-gear, and including bevel-gears and a vertical shaft driven thereby and carrying a gear intermeshing with said spindle-gear, and automatic feed appliances likewise driven from 105 said motor-shaft.

In testimony whereof I affix my signature in the presence of two witnesses.

CHARLES E. WILLEY.
